UNITED STATES PATENT OFFICE.

GEORGE H. FORSYTH, OF CHICAGO, ILLINOIS, ASSIGNOR TO WAUGH DRAFT GEAR COMPANY, A CORPORATION OF ILLINOIS.

DRAFT AND BUFFING APPLIANCE FOR RAILWAY-CARS.

1,090,143.

Specification of Letters Patent. Patented Mar. 17, 1914.

Application filed June 16, 1908. Serial No. 438,825.

To all whom it may concern:

Be it known that I, GEORGE H. FORSYTH, a citizen of the United States, residing at Chicago, in the county of Cook and State of Illinois, have invented certain new and useful Improvements in Draft and Buffing Appliances for Railway-Cars, of which the following is a specification.

This invention relates to draft and buffing appliances for railway cars; and among the principal objects sought by the invention are: to relieve the draw-bar of breaking or other injurious shocks and strains under coupling or other buffing action, which is accomplished partially through the provision of a draw-bar cushioning device interposed in the draw-bar itself and partially by means of a buffing mechanism which transmits the buffing strains directly to a buffer-cushioning device also located in the draw-bar near its rear end and, in the case of excessive strains, to the main resistance medium of the gear without transmitting such strains through the major portion of the draw-bar itself; to provide a yielding and elastic connection between the draw-bar and buffer-stem through which the side movements of the former are transmitted to the latter; to provide an improved antifriction support for the draw-bar on the hanger; to provide an adjustable means for effecting the side swing of the draw-bar from the angular movement of the truck relatively to the car-body; and to effect other improvements which will be apparent from the following description.

My invention, in one practical form in which the same may be embodied, is illustrated in the accompanying drawings, in which,—

Figure 1 is a top plan view of the appliance, showing also parts of the car to which it is applied. Fig. 2 is a side elevation, partly in vertical section, of the parts shown in Fig. 1. Figs. 3 and 4 are enlarged cross-sectional details on the lines 3—3, 4—4, respectively, of Fig. 1. Figs. 5 and 6 are similar enlarged cross-sectional details on the lines 5—5 and 6—6, respectively, of Fig. 2.

Referring to the drawings, 10 designates as a whole a cast steel platform adapted to be secured to the end of a car-body, opposite the forward end transverse portion 10^a of which platform is located a buffer-beam 11.

12 designates a buffer-stem that is slidably

mounted in and through the buffer-beam and platform casting and has pivotally secured to its forward end by a pivot-pin 12^a and a cotter-pin 12^b a buffer-plate 13, this latter being backed by a block 14 preferably constituting an integral thickened portion of the buffer-plate and having an inner face conforming to and adapted to contact with the forward end of the buffer-beam 11 under the extreme inward thrust of the buffer-plate.

The draw-bar is made in two sections, a main section 15, the forward end of which has a rectangular socket 15^a, and in rear thereof a round socket 15^b, and a coupler section comprising the coupler head 16 and coupler shank 17, this latter having a sliding fit in the square socket 15^a of the section 15. Within the round socket 15^b is a coil spring 18 constituting a draw-bar cushioning spring which abuts against the inner end of the coupler shank 17 and absorbs buffing shocks upon the coupler head up to a point at which the inner end of the shank abuts against the shoulder portions 15^c surrounding the mouth of the socket 15^b.

The rear end of the section 15 of the draw-bar has a pivotal connection through a pivot-pin 19 with the usual yoke 20 of the draft-rigging, within which yoke are front and rear followers 21 and 22 having convex and concave inner faces, respectively, and a series of interposed groups of flat spring plates 23, between which latter are intermediate followers 24; the adjacent faces of adjacent followers being concave and convex, respectively, so as to produce a bending effect upon the spring plates under both draft and buffing strains. The yoke, followers, and spring-plates together constitute what I term herein the "draft-rigging".

The draw-bar section 15, slightly in advance of its pivotal point, is vertically offset, as shown in Fig. 2, which offset portion is somewhat widened and formed with a socket or chamber 25 open at its front end, and within which are located a pair of coiled compression springs 26, opposite the forward end of which is a follower-plate 27 having a concave forward face 28 against which abuts the inner rounded end of the buffer-stem 12. The buffer-stem is connected with the chambered portion of the draw-bar with capacity for a sliding movement therein by means of a transverse key 29 pass-

ing through the inner end of the buffer-stem and through longitudinal slots 30 formed in the sides of the chamber. A similar connection is employed for preventing displacement of the coupler stem 17 from the draw-bar section 15, consisting of a transverse key 31 passed through the coupler stem and through longitudinal slots 32 in the sides of the chambered end of the member 15.

33 designates the usual supporting carry-iron for the draw-bar, the same being shown as of I-beam form and having its horizontal section curved on an arc struck from the pivotal center 19 of the draw-bar, the ends 15 of the carry-irons being attached to the car as by the brackets 33^a. The forward chambered end of the draw-bar section 15 seats in a saddle 34 directly above the hanger 33, which saddle has depending fore and aft 20 legs 35 in which are journaled a series of rollers 36 that ride on the lower flange of the I-beam hanger 33.

Referring next to the elastic or yieldable connection between the draw-bar and buffer-stem whereby lateral swinging movement of the former is transmitted to the latter, 37 designates each of a pair of upstanding projections on the draw-bar section 15 herein shown as located directly above the spring 30 chamber or socket 15^b, between which are located a pair of oppositely facing socketed followers 38 which confine between them a coiled compression spring 39. It will be observed by reference to Fig. 5 that the ends 35 of the followers 38 project beyond the vertical edges of the lugs 37, as shown at 38^a. Embracing the buffer-stem 12 is a yoke 40 having depending end projections 40^a that overlap the front and rear edges of the 40 projections 37, and are centrally channeled to receive the ends 38^a of the followers 38. The projections 37 are preferably connected by a tie-bolt 41 that is axially coincident with the spring 39 and that serves to transmit the lateral strains from one projection to the other, distributing the strains between them. From the foregoing it will be seen that the lateral swing of the draw-bar effects, through one of the upstanding projections 37, a thrust upon the follower member 38 in contact therewith, which latter, through the spring 39, transmits the thrust in an elastic form to the opposite follower, the ends 38^a of which transmit this lateral thrust to the depending extensions 40^a of the yoke 40, which latter transmits the thrust to the buffer-stem. By this means the side swing of the draw-bar and coupler-head is transmitted in an elastic and yielding manner to the buffer-stem and consequently to the buffer-plate carried at the forward end of the latter, thus relieving the connecting means between the draw-bar and buffer-stem of sudden breaking shocks.

65 The draw-bar and buffer mechanism are

controlled as to their lateral swinging movements by the truck through connections from the latter to the draw-bar section 15, which connections, as herein shown, comprise, on each side of the draw-bar, a connecting chain 42 provided with an elastic extensible section 42^a, said connecting chain being joined at its ends to clevises 43 and 44 which, in turn, are pivotally connected to brackets 45 and 46 secured respectively to the truck-frame 47 and draw-bar section 15. To provide for an adjustment of the truck connections which will afford varying extents of swing of the draw-bar from the relative angular movement between the truck and car-body, when on curved track, the brackets 45 and 46 are provided with a plurality of pivot-holes 45^a and 46^a to which the clevises 43 and 44 may be pivoted. Instead of these brackets 45 and 46 it is evident that other adjusting means might be employed.

Referring once more to the connection between the buffer-plate and buffer-stem, it will be observed by reference to Fig. 1 that the buffer-stem has, near its forward end, a pair of lateral projections 48, between which and the inner face of the buffer-plate on either side of the buffer-stem are interposed compression springs 49 operating to maintain the buffer-plate substantially normal to the buffer-stem when the car is uncoupled, and at the same time permitting freedom of angular movement of the buffer-plate to allow the latter to accommodate itself to possible angular impact of another buffer-plate.

I claim:

1. In a draft and buffing appliance, the combination with a draw-bar capable of lateral swinging movement, of a buffer-plate having a stem also capable of lateral swinging movement, and a connection between said draw-bar and buffer-stem permitting both a lateral movement of said buffer-stem relatively to, and a bodily lateral movement of said buffer-stem with, said draw-bar.

2. In a draft and buffing appliance, the combination with a laterally swinging draw-bar and buffer-stem, of a yielding connection therebetween adapted to transmit the lateral movement of the former to the latter, said connection comprising overlapping upstanding and depending projections from said draw-bar and buffer-stem, respectively, and an interposed spring member and interlocking connections between said projections.

3. In a draft and buffing appliance, the combination with a laterally swinging draw-bar and buffer-stem, of a connection therebetween adapted to transmit the lateral movement of the former to the latter, said connection comprising overlapping upstanding and depending projections from said draw-bar and buffer-stem, respectively, a pair of followers, and an interposed spring,

said followers and spring serving to transmit movement between said projections.

4. In a draft and buffing appliance, the combination with a draw bar capable of lateral swinging movement, of a buffer plate having a stem also capable of lateral swinging movement, and a yieldable connection between said draw bar and buffer stem permitting both a lateral movement of said buffer stem relative to and a bodily lateral movement of said buffer stem with said draw bar, said connection including means to positively limit the extent of such relative lateral movement, substantially as described.
5. In a draft and buffing appliance, the combination with a lateral swinging draw bar and buffer stem, of a connection therebetween adapted to transmit the lateral movement of the former to the latter, said connection comprising interengaging rigid members carried by the draw bar and buffer stem respectively and providing for limited lateral relative movement, and a spring interposed between said rigid members, substantially as described.
6. In a draft and buffing appliance, the combination with a lateral swinging draw bar and buffer stem, of a connection there-

between adapted to transmit the lateral movement of the former to the latter, said connection comprising overlapping upstanding and depending projections from said draw bar and buffer stem, and an interposed spring, the coaction of said projections and spring serving to yieldingly transmit movement between said draw bar and buffer stem, substantially as described.

7. In a draft and buffing appliance, the combination with a lateral swinging draw bar and buffer stem, of a connection therebetween adapted to transmit the lateral movement of the former to the latter, said connection comprising overlapping upstanding and depending projections from said draw bar and buffer stem respectively, a pair of followers arranged between the members of one set of projections and interlocking with the members of the other set of projections, and a spring interposed between the followers, said followers and spring serving to yieldingly transmit movement between the two sets of projections, substantially as described.

GEORGE H. FORSYTH.
